UNITED STATES PATENT OFFICE

132,016

DESIGN FOR A MERCHANTISE DISPLAY CASE UNIT

José Trojan, Chicago, Ill., assignor to Owen Housholder and David C. Cohen, copartners, doing business as Crystal Manufacturing Co., Chicago, Ill.

Application February 2, 1942, Serial No. 105,574

Term of patent 3½ years

To all whom it may concern:

Be it known that I, José Trojan, a citizen of the United States, residing at Chicago, in the county of Cook and State of Illinois, have invented a new, original, and ornamental Design for a Merchandise Display Case Unit, of which the following is a specification, reference being had to the accompanying drawing, forming part thereof.

dise display case unit embodying my new design;

Figure 2 is a front elevational view thereof; and

I claim:

The ornamental design for a merchandise display case unit, substantially as shown.

JOSÉ TROJAN.
